ATTORNEY

UNITED STATES PATENT OFFICE.

JESSE P. MAYHUGH, OF GLASSPORT, PENNSYLVANIA.

PORTABLE EXTENSIBLE SUPPORT.

Application filed March 31, 1922. Serial No. 548,318.

To all whom it may concern:

Be it known that I, JESSE P. MAYHUGH, a citizen of the United States, residing at Glassport, in the county of Allegheny and 5 State of Pennsylvania, have invented certain new and useful Improvements in Portable Extensible Supports, of which the following is a specification.

This invention relates to a portable extensible support, primarily designed to supersede ladders, scaffolding, swinging platforms, etc., utilized by workmen on work accessible only by the use of such structures, but it is obvious that the device may be employed for any purpose wherein it is found to be applicable.

Important objects of the invention are to provide an elevating device of the type stated, in a manner as hereinafter set forth, 20 which is self supporting and need not be attached to any structure for maintenance, which may be manipulated by an operator on the elevating platform, which is simple in its construction and arrangement, readily 25 positioned, compactly collapsible for transportation or storage, durable and efficient in its use, and inexpensive to manufacture.

To the accomplishment of these and such other objects as may hereinafter appear the 30 invention consists of the novel construction, combination and arrangement of parts herein specifically described and illustrated in the accompanying drawing, wherein is shown an embodiment of the invention, but 35 it is to be understood that changes, variations and modifications may be resorted to which come within the scope of the claims hereunto appended.

In the drawing forming a portion of the 40 specification and wherein like numerals of reference designate corresponding parts throughout the several views:—

Figure 1 is a side elevation of an extensible support in accordance with the invention.

Figure 2 is an end view thereof.

Figure 3 is a top plan view of the device.

Figure 4 is a sectional view on line

IV—IV, Figure 1.

Referring in detail to the drawing 1 denotes an elongated base, preferably constructed from channel iron and having longitudinally adjustable ends 2, each provided with a pair of depending legs 3, 4. The 55 lower end of each of the legs carries a vertically adjustable roller 5 to permit of and

facilitate the leveling and positioning of the device.

A vertically extending bracket 6 is fixed to the base 1 and is formed with a guideway 60 7 and slot 8. A vertically disposed and shiftable rack bar 9 is slidably mounted in the guideway 7, and carries a rearwardly extending arm 10 to which the operating cable 11 is anchored. 65

Supported from the upper end of the bracket 6 is an extensible member 12, operable on the well known lazy tongs system, and comprises a plurality of jointed bars capable of great extension. The lower pair 70 of bars 13, 13' are pivotally connected as indicated at 14, to the upper end of the bracket 6. The ends of the cable 11 are connected, as at 15, to respective bars 13, and 75 13'.

The free ends of each of the upper pair of bars 16 and 16' carries a pair of pivotally supported rollers 17, which operate in a runway 18, secured to the lower face of the platform 20 and connect the latter with the extensible member 12. The lower face of the runway 18 is provided with a slot 21 to allow the movement of the bars 16, 16', therein when the member 12 is extended or collapsed. 80 Each of the bars 16 and 16' is formed with a head 22 having an aperture 23 for the reception of the pin 24, which extends through the platform 20 and serves to lock the member 12 to the adjusted position by preventing movement thereof. 85

A pinion 25 is in mesh with the rack bar 9 and is fixed to the shaft 26 journaled in the bearings 27 mounted in the bracket 6. A drive gear 28 is fixed to one end of the shaft 26 and meshes with the pinion 29 on the shaft 30, journaled in the bearing 31 and bearing bracket 32. The former is secured to the bracket 6 and the latter to the base 1. 90

Fixed to the shaft 30 is a drum 33 on which the operating rope 34 is adapted to 100 be coiled. When the rope 34 is pulled by the operator the drum 33 is rotated, actuating the gear mechanism and thereby shifting the rack bar 9 vertically downward. Such movement of the rack bar 9, due to its connection with the extensible member 12 through the cable 11, will cause the extension of the member 12 and elevate the platform 20 carried thereby. The collapse of the member 12 is by gravity, during which 105 operation the rope 34 is rewound on the drum 33. 110

To stabilize the platform 20 when elevated to the adjusted position a plurality of guy lines 35 are provided, each of which has one end attached to the base 1, as at 36, and the other to the platform, as at 37.

An operator on the platform 20 may readily elevate himself and the platform 20 to any desired height by manipulating the rope 34 to actuate the gear mechanism and associated parts as above described.

What I claim is:—

1. A support of the type described comprising a platform having depending from its lower face a slotted runway, a base, an extensible supporting element mounted on the base and extended through the slot of the runway, means carried on the upper end of said element and travelling on said runway whereby said element is slidably connected with said platform, means for operating said element to vertically adjust said platform, and means carried by the platform for maintaining it in adjusted position.

2. A support of the type described comprising a platform having depending from

its lower face a slotted runway, a base, an extensible supporting element mounted on the base and extended through the slot of the runway, means carried on the upper end of said element and travelling on said runway whereby said element is slidably connected with said platform, means for operating said element to vertically adjust said platform, and means for adjusting the length of the base and for leveling the same.

3. A support of the type described comprising a platform having depending from its lower face a slotted runway, a base, an extensible supporting element mounted on the base and extended through the slot of the runway, means carried on the upper end of said element and travelling on said runway whereby said element is slidably connected with said platform, means for operating said element to vertically adjust said platform, and means carried by the platform and engaging said element for maintaining the platform in adjusted position.

In testimony whereof I affix my signature. 50

JESSE P. MAYHUGH.
